(57) CLAIM

The ornamental design for a wallet, as shown and described.

DESCRIPTION

FIG. 1 is a top, facing, left perspective view of our new design for a wallet;]

FIG. 2 is a top plan view thereof;]

FIG. 3 is a bottom plan view thereof;]

FIG. 4 is an elevated facing view thereof;]

FIG. 5 is an elevated rear view thereof;]

FIG. 6 is an elevated left side view thereof; and,]

FIG. 7 is an elevated right side view thereof.]

FIG. 8 is a top, facing, left perspective view of our new design for a wallet;

FIG. 9 is a top plan view thereof;

FIG. 10 is a bottom plan view thereof;

FIG. 11 is an elevated facing view thereof;

FIG. 12 is an elevated rear view thereof;

FIG. 13 is an elevated left side view thereof; and,

FIG. 14 is an elevated right side view thereof.

Dotted lines of equal length shown in the Figures represent stitching that forms part of the claimed design. Dotted lines of alternating long and short dashes represent [unclaimed subject matter] portions of the wallet that forms no part of the claimed design. [Separation lines in the drawings show indeterminate length, and the space between separation lines is unclaimed.] The wallet is shown with a symbolic break in its length. The appearance of any portions of the wallet between the break lines forms no part of the claimed design.

1 Claim, 6 Drawing Sheets

Matter enclosed in heavy brackets [ ] appears in the original patent but forms no part of this reissue; matter printed in italics indicates the additions made by reissue.
